UNITED STATES PATENT OFFICE.

WILHELM HIRT, OF PITTSBURG, PENNSYLVANIA, ASSIGNOR OF ONE-HALF
TO CUNNINGHAMS & CO., OF SAME PLACE.

GLASS-MAKER'S CRANE.

SPECIFICATION forming part of Letters Patent No. 234,777, dated November 23, 1880.

Application filed October 20, 1880. (No model.)

To all whom it may concern:

Be it known that I, WILHELM HIRT, of Pittsburgh, in the county of Allegheny and State of Pennsylvania, have invented a new and useful Improvement in Glass-Makers' Cranes, &c.; and I do hereby declare the following to be a full, clear, and exact description thereof, reference being had to the accompanying drawings, forming part of this specification, in which—

Figure 1 is a side elevation of my improved crane, and Fig. 2 is a plan view of the same.

Like letters of reference indicate like parts wherever they occur.

15 My invention relates to an improvement in glass-blowers' cranes, and is an improvement on the crane invented by me and forming the subject of Patent No. 223,348, dated January 6, 1880; and it consists in mechanical devices 20 so as arranged as to give an easy and free movement to a swinging crane having an extension-arm, which is projected by a crank operated by gearing from the shaft of the crank, so that the angle of presentation of the 25 cylinder of glass is always the same, or nearly so, so that as the pipe is moved toward or from the furnace it always travels in a right line.

In the former device used by me, described 30 in Patent No. 223,348, the crane was found to be somewhat cumbersome and hard to work, owing to the friction between the arm of the crane and the extension-rod. This difficulty has been obviated by my invention, which I 35 will now proceed to describe, so that others skilled in the art may manufacture and use the same.

The crane *a* is composed of a frame having a horizontal arm, *b*, and braces *b'* *b*², the whole 40 being pivoted at the points *c' c*' to a plate, *d*, which plate is fastened to an iron post by bolts or screws. On the plate *d*, just above the lower pivotal connection *c'* with the frame *a*, is a pinion, *e*, consisting of a segment of a circular plate, the edge or circumference of which is provided with cogs. Meshing in this pinion *e* is another pinion, *e'*, on a shaft, *f*, which shaft is mounted on the side of the frame *a*, and extends to the top thereof parallel to the 45 plate *d*. This shaft *f* has an arm, *h*, at its up-

per end, which extends back. From the outer end of this arm *h* a rod, *i*, runs forward, and is fastened to a slide or extension, *k*, placed on top of the arm *b*, and sliding between friction-rollers *l l*, which extend up from both sides of 55 the arm *b*. The number of these rollers *l* may be increased or diminished, as is found necessary; but four will generally be found sufficient, one on each side of extension-rod *k* at the end of the arm *b*, and one on each side of the rod 60 *k* at a point midway between the end of the arm *b* and the plate *d*. Forward of this point is a yoke, *m*, extending up from the arm *b* on both sides of the rod *k*, and in this yoke, above the rod *k*, is mounted a bearing-wheel, *m'*. 65

At the end of the arm *b* below, and upon which the extension-rod *k* travels, is another bearing-wheel, *m*². At the outer end of the extension-rod *k* is a pivoted bearing, *n*, upon which the blow-pipe rests. 70

The glory-hole of the furnace is shown by the dotted line in Fig. 1 at *p*, and the pit below the crane at *p'*. The crane when at right angles to the plate *d* stands in its normal condition with the extension-rod *k* lying back on the arm *b* and the bearing for the blow-pipe over the pit *p'*; but when it is desired to insert the cylinder of glass on the end of the blow-pipe in the glory-hole, by moving the crane in that direction the gear-wheel *e'* and 75 shaft *f* turn, and by means of the crank-arm *h* and rod *i* cause the extension-arm *k* to move forward, so that the pipe-bearing *n* on the end of the same shall move in a right line tangent to the arc of the circle which the end of the 80 arm *b* describes, and thereby keep the bearing of the blow-pipe on a right line with the center of the glory-hole. 85

The advantages of my improvement over my former device are, that by placing the pinions *e e'* at a greater distance from the end of the arm *b* a greater leverage is obtained. The friction is lessened by the use of the side rollers, *l l*. The shaft *f*, instead of passing through the arm *b* and brace *b'*, passes along the side 90 of the same, and is fastened by means of boxes *r*, thereby allowing the thickness of said arm and braces to be materially reduced. The arm *l* and braces *b'* and *b*² are preferably cast in one 95 piece, so as to form a frame strong and at the 100

same time light and compact. The pivotal connections *c c* to the plate *d* form a substitute for and do away with the shaft of the crane as used in the former device. The crane works 5 with a free and more regular motion. It is much stronger and takes up much less room than the former device.

Having thus described my invention, what I claim, and desire to secure by Letters Patent, is—

In a swinging crane, the combination of an

arm, *b*, braces *b' b²*, slide or extension arm *k*, friction-rollers *l l*, rod *i*, crank-arm *h*, shaft *f*, pinions *e e'*, and plate *d*, substantially as and for the purpose described.

In testimony whereof I have hereunto set my hand.

WILHELM HIRT.
